[57] CLAIM

The ornamental design for an automobile tire, as shown and described.

DESCRIPTION

FIG. 1 is a perspective view of an automobile tire showing our new design, it being understood that the tire tread pattern is repeated throughout that circumference of the tire, the opposite side being substantially the same as that shown;

FIG. 2 is an end elevational view thereof;

FIG. 3 is a side elevational view thereof; and

FIG. 4 is an enlarged fragmentary developmental plan view thereof.

FIG. 1

FIG. 2

FIG. 3

FIG. 4
